CLARENCE S. JACKSON, OF NEW YORK, N. Y., ASSIGNOR OF ONE-HALF TO
SEPTIME S. SANGUINETTE, OF NEW YORK, N. Y.

CELLULAR BOTTLE OR CONTAINER.

No. 854,357.

Specification of Letters Patent.

Patented May 21, 1907.

Application filed June 19, 1906. Serial No. 322,394.

To all whom it may concern:

Be it known that I, CLARENCE S. JACKSON, a citizen of the United States, residing in the borough of Manhattan, in the city of New York, county of New York, and State of New York, have invented certain new and useful Improvements in Cellular Bottles or Containers, of which the following is a specification.

This invention relates to and has for an object to provide an improved cellular bottle or container for commodities, as for instance liquid, in a number of divided and separated bodies or portions, and provides means whereby each body or portion may be removed from its cell independently of the others and without disturbing the same.

The device is more particularly adapted for use in dispensing liquids which will ordinarily be dispensed or consumed in uniform quantities, and will comprise a body portion of some suitable material having within it a number of cells, which may be of the proper size for receiving a proper predetermined amount of the liquid, and if such liquid is a beverage or liquor each cell will have the capacity for the quantity which is usually served for a single drink of that particular commodity. The cells will be so closed that each one may be opened individually and its contents removed without interfering with the contents of the other cells or with the closures therefor. The closure may be so arranged relative to the cells that some trade-mark feature or a seal or stamp may be broken or canceled upon opening each cell so that when all the cells have been opened the trade-mark will be effectively destroyed or the set of stamps or seals completely canceled, thus preventing refilling and resale under the former designations of origin or compliance with governmental regulations.

The invention also embodies a device for breaking the seal or closure for each chamber and for pouring off the contents of the same, constituting, as it were, the bottle neck if the container is regarded as a bottle.

In the drawings accompanying and forming a part of this specification Figure 1 illustrates, in perspective, a form of the present improvement. Fig. 2 is a central vertical

section of the device shown in Fig. 1, the bottom portion, however, being broken away. Figs. 3 and 4 are plan views of other forms or shapes of the container. Fig. 5 is a side view of a form of device for breaking the closure or seal and serving as a pouring mouth for dispensing the contents from the several cells. Fig. 6 is a view of the point or puncturing portion of the same. Fig. 7 is an end view of the device seen in Fig. 5. Fig. 8 is a side view of the device shown in its position after having punctured the seal or closure and obliterated or canceled some distinctive portion of the design thereon, it being shown in a position where it may be employed as a pouring port for the cell or compartment which it has entered; and Fig. 9 is a perspective view illustrating the seal breaking device and the seal after the said device has been removed therefrom.

The body portion 20 of the container may be made of some suitable material impervious to the liquid which it is intended shall be packed therein, and it will then be made or coated with some material which will not be attacked by the material to be contained or injuriously affect the flavor of the same. The body portion may be of glass and be provided with a number of receptacles or cells 21 which will extend nearly to the bottom of the body portion, and each of these cells may be made of the capacity to contain the amount of the commodity which appears to be the average amount of this particular commodity which will generally be consumed at one time. One of the cells, as 22, may be made for the reception of an opener or seal breaking device, and for convenience this may be the midmost chamber, and if the opening device is short, as is herein illustrated, the chamber may be of corresponding length, which will leave a centrally disposed spine 23 throughout nearly the entire length of the structure; this will add a certain amount of stability and support. A flange, indicated by 24, Fig. 2, may be provided at the top of the body. In the present illustration the openings of the chambers or receptacles are all on a plane and surrounded by said flange, the cells all opening at the face 26 of the body portion, which represents the

plane of the chamber openings. The flange 24 will be of sufficient height to accommodate a suitable closure, designated in a general way by 27, which in the present instance 5 is shown as comprising a piece of cork 28 and a piece of paper 29 imposed thereon. The closure will be embraced within the flange 24. The paper, of course, may bear whatever printing matter or illustrations are 10 found desirable, and may consist of a trademark, a stamp or a seal having a number of separated and distinct elements or designs, designated by 40, and each of which will be so placed relative to a cell mouth that the 15 opener will cancel or mar that particular element in opening the cell, and when all the cells have been opened, the stamp, trademark, or seal will be so thoroughly obliterated or defaced, that fraudulent refilling will 20 be readily detected and thereby rendered commercially impossible.

The opening device, designated in a general way by 30, is shown in position in Fig. 2, and is located in such a manner that the closure 27 in passing over the face 26 also passes over the top of the opener, which opener is 25 shown as having a flange or undercut mouth portion 31 occupying when in position a countersink 25 or flaring end of the cell 30 22. The portion 31 will not only assist in the removal of the opener from the cell which is intended to contain it, but will also provide a flaring pouring mouth when this is used for pouring purposes in discharging 35 the contents of a cell. In the form illustrated herein the opener comprises a substantially cylindrical body portion 32 which is in the form of a tube and has within it some suitably formed knife for incising the seal or 40 closure and obliterating the design on the seal or closure above the cell which it is employed to open. This in the present instance is shown as a cruciform blade 33 having a pointed end 34, which when applied to the 45 closure will make a cruciform incision, as indicated at 35 in Fig. 9, and upon the passage of the body portion 32 within such opening the flaps 36 will closely embrace said body portion and make a secure and liquid tight 50 joint. It may be that at times less than the entire contents of a cell will be withdrawn, and in which event the opener may be permitted to remain in place in the opened cell and may be closed by a stopper 45 of some 55 suitable material.

After the package has been filled with the desired commodity the closure 27 will be properly applied whereby it will seal each of the receptacles or cellular chambers, and will 60 also hold the opening device within its compartment. All of the cells may be filled with the same commodity or they may each be filled with a different commodity, whereby a

sample case, of liquors for instance, may be put up in this convenient manner.

The shapes shown in Figs. 1 and 4 are such that containers made in these shapes may be readily packed in a very compact form for shipment or storage. It will also be seen that there is no outwardly extending bottle 70 neck, the top of the device being square when the neck, which is interchangeable for all the cells, is not in an operative position. This gives, for purposes of packing and storage, a neckless bottle. If it was attempted to pour 75 the contents from one of the cells across the face of the closure this would become very much soiled, and while the stream was passing over such stop it would find entrance perhaps into some of the previously opened 80 cells; but the opener 30 serves as a bottle neck for each compartment, whereby the pouring mouth 31 is brought to a suitable distance beyond the closure 27 which will enable a free and ready pouring of the liquid.

The body of the opening device when made slightly tapering will securely jam the in-turned portions of the seal or closure against the inside of the cells. This not only acts as a packing, as was before alluded to, but also 90 will prevent any of the portion of the closure which is forced into the cell in the opening thereof from becoming disengaged and being floated out with the liquid as it is poured out.

Having described my invention I claim: 95

1. In a device of the character specified, the combination with a body portion having a plurality of cells for containing liquid, of a breakable cover for said cells.

2. In a device of the character specified, the combination with a body having a plurality of cells opening upon a common plane, of a breakable closure for said cells, said closure being provided with a distinct configuration above the mouth of each of said cells.

3. In a device of the character specified, the combination with a body having a plurality of cells, of means for closing said cells and an interchangeable pouring mouth for said cells provided with a portion for opening the cell closing means.

4. In a liquid container, the combination with a body portion having a plurality of open cells, said openings being closely assembled, of means for closing said cells, and an interchangeable pouring neck and mouth for said cells.

5. In a device of the character specified, the combination with a body portion having within it a plurality of cells, all but one of said cells being adapted to contain liquid, of an opening device for the closure for said cells located within said excepted cell, and a closure for all of said cells.

6. In a device of the character specified, the combination with a body portion having

rectangular sides and ends, said body portion having a number of cells provided with openings in one of the ends of said body, of means for closing said cells, and an interchangeable 5 pouring neck and mouth for said cells for bringing the pouring point above the common plane of said cell mouths.

Signed at Nos. 9-15 Murray street, New York, N. Y., this 6th day of June, 1906.

CLARENCE S. JACKSON.
